UNITED STATES PATENT OFFICE.

JOHN W. WELCH, OF CHICAGO, ILLINOIS, ASSIGNOR OF ONE-FOURTH TO EDWARD L. CHOTT AND ONE-FOURTH TO HUGO J. CHOTT, OF CHICAGO, ILLINOIS.

DENTAL-ENGINE STONE AND MANDREL.

1,077,572.

Specification of Letters Patent.

Patented Nov. 4, 1913.

Application filed October 7, 1912. Serial No. 724,352.

To all whom it may concern:

Be it known that I, JOHN W. WELCH, a citizen of the United States, and a resident of the city of Chicago, county of Cook, and 5 State of Illinois, have invented certain new and useful Improvements in Dental-Engine Stones and Mandrels, of which the following is a specification.

My invention relates to improvements in 10 dental-engine stones and mandrels and has for its object the production of a dental-engine stone and mandrel which will be so connected as to absolutely prevent relative rotary movement of said stone and mandrel 15 so as to permit of rotation of the stone or abrasive element in either direction without fear of the latter becoming loosened.

A further object is the production of a 20 stone and mandrel of the character mentioned which will be so connected as to permit of ready and expeditious detachment of the stone when desired in order to permit of replacement of the stone or for any other reason.

25 A still further object is the production of a tool of the character mentioned which will be of simple and economical construction and efficient in use.

Other objects will appear hereinafter. 30 The invention consists in the combinations and arrangements of parts hereinafter described and claimed.

The invention will be best understood by 35 reference to the accompanying drawing forming a part of this specification, and in which,

Figure 1 is a sectional side elevation of a 40 dental-engine stone and mandrel embodying my invention. Figs. 2 and 3 are perspective views of the mandrel and stone disconnected, and Figs. 4 and 5 and 6 and 7 are views similar to Figs. 2 and 3, respectively, showing slightly modified forms of the construction.

45 The preferred form of construction as illustrated in the drawings comprises a cylindrical mandrel 1 provided at one end with a circumferential flange or shoulder 2. Arranged at said end of said mandrel is the 50 stone or abrasive element 3 which is detachably secured to said mandrel by means of a headed screw 4 which passes centrally through the stone 3 and which is threaded in a threaded socket 5 formed centrally in 55 the adjacent end of said mandrel. The

flange 2 engages, as shown, a recess 6 which is formed in the adjacent side of the stone 3, said recess passing only partly through said stone, so that the stone will be clamped in position between the outer end of the 60 mandrel and the head of the screw 4. Said flange 2 is of polygonal or rectilinear form in cross-section and the recess 6 is of corresponding form so that the stone and mandrel will be absolutely locked against relative rotary movement. Said flange and recess may be of any one of a variety of different forms it being only essential that the same are not circular since with the latter construction the absolute locking of the 70 stone and mandrel against relative rotary movement would not be secured.

With a dental-engine stone and mandrel of the construction set forth it will be seen that the stone is securely fastened to the 75 mandrel against relative movement in all directions, but in such a manner that the same may be readily and expeditiously detached when desired in case the stone becomes worn or disabled or in order to permit of another stone being secured in its place, this being effected by simply removing the securing screw 4. With this arrangement a dentist needs only to be equipped with one mandrel since the same 80 will be adapted for use in conjunction with any stone which is recessed to correspond therewith. A great saving will be thus secured as will be appreciated by those skilled in the art. The outer end of the socket 5 90 is counter-sunk in order to facilitate insertion of the point of the screw in the attachment of a stone to the mandrel.

While I have illustrated and described the 95 preferred form of construction for carrying my invention into effect, this is capable of variation and modification without departing from the spirit of the invention. I, therefore, do not wish to be limited to the precise details of construction set forth, 100 but desire to avail myself of such variations and modifications as come within the scope of the appended claims.

Having described my invention what I 105 claim as new and desire to secure by Letters Patent is:

1. The combination of a mandrel; an abrasive element arranged at one end of said mandrel, said mandrel end fitting snugly a recess formed in one side of said 110

element extending partly through the latter; and means for locking said abrasive element to said mandrel, said recess and engaging end of said mandrel being of corresponding non-circular form, substantially as described.

2. The combination of a mandrel; an abrasive element arranged at one end of said mandrel, said mandrel end fitting snugly 10 a recess formed in one side of said element extending partly through the latter; and means in threaded connection with said

mandrel for locking said abrasive element to said mandrel, said recess and engaging end of said mandrel being of corresponding non-circular form, substantially as described. 15

In testimony whereof I have signed my name to this specification in the presence of two subscribing witnesses.

JOHN W. WELCH.
